GLOVE AND METHOD OF MAKING SAME
FROM STRIP MATERIAL

Joseph Bloom, New York, N. Y.

Application October 2, 1937, Serial No. 166,941

7 Claims. (Cl. 2—169)

My invention relates to a novel glove composed of a plurality of strips of glove material and the method of making the same and more specifically relates to a novel glove comprising a plurality of strips of glove material joined together at the edges to form fingers and laterally secured one to the other to form the top and palm portion of the glove and the process of making the same.

10 It is customary according to the prior art to manufacture gloves by laying a pattern upon a sheet of suitable material such as a fabric or leather and cut out a glove to the desired configuration. Two suitably cut sections are joined together with a kyle at the sides of the fingers to provide proper spacing between the two glove sections and to provide proper fitting for the fingers. At those points where the fingers meet the palm and between the fingers are fourchettes which are used to provide a proper fitting and to give a proper shape to the glove.

15 There are a multiplicity of operations requiring skilled labor of a high degree in the manufacture of gloves according to the present process. The manufacture of a glove not only requires skilled labor but also extended time, factors which go towards making a glove a comparatively high priced article of wearing apparel in view of the comparatively small amount of raw material employed. In other words, the cost of a glove lies largely in the cost of the labor involved in this manufacture.

20 It is the primary object of my invention to provide a novel process for producing a glove by means of a few simple manufacturing steps requiring unskilled labor.

25 The novel glove of my invention is further, because of the method of manufacture, an extremely attractive article characterized by form fitting qualities and good wearing properties.

30 The manufacture of my novel glove involves the use of a plurality of strips of any desired material such as silk, wool, rayon or the skins of any material may be used that can be formed into strips. These strips are the elements of the process of my invention and can be formed, if a knitted material is to be used, on a Rochel, flat or Jacquard knitting machine or any knitting machine that can produce a long, narrow strip of fabric. Preferably, the edges of this fabric are welted to provide against subsequent unravelling and also to facilitate lateral securing with similar strips during the manufacture of the glove from these strips. As will be described more fully hereinafter, the strips are longitudinally aligned with re-

spect to the length of the glove, a single strip forming a single finger and a single strip forming both thumb and index finger. A strip of the desired material may be folded or two strips, superimposed one upon the other, may be secured by stitching so that no internal seams that are objectionable from the standpoint of discomfort to the wearer, are produced.

35 It is an important feature of my invention that I can produce a square finger tip by the process of folding over the strip of material at said finger tip and closing the sides by ordinary stitching. I can also secure the square tip by superimposing two strips and stitching the two strips together in proper form to provide a finger and body portion for the glove. If desired I can produce a round tip finger by suitably cutting the strip or strips at the finger end to the desired shape and then stitching them together. I have also found it possible to regulate the shape of the finger tip by the spacing of the stitching from the edge of the strip, and the shape of the line of stitching. This finger tip shape applies whether I use two superimposed strips or a single overlapping strip of material.

40 I have also formed a very novel and decorative glove by spacing the strips of material laterally at a distance, one from the other, and securing them in that position by a decorative stitching. Thus I have formed an open-work glove with a lace-like appearance which is of great value for summer wear.

45 It is the object of my invention to provide a novel process for simply manufacturing a glove with a minimum of manufacturing steps.

50 It is the further object of my invention to provide a novel process of assembling strips of suitable material in longitudinal alignment to form a glove.

55 It is the further object of my invention to assemble two strips of material, one superimposed upon the other, and to secure said superimposed strips at the edges to form a finger portion for a glove.

It is a further object of my invention to provide a novel decorative glove comprising strips of glove material.

60 It is a further object of my invention to provide a glove with strips of varying width so that differences in finger widths on a single hand may be compensated for to provide a well fitting glove.

65 It is a further object of my invention to provide a glove in which the thumb and index finger may be formed by a single strip of material.

70 It is a further object of my invention to pro-

vide a novel glove in which the thumb may be formed and inset by a single strip of material.

It is a further object of my invention to provide a novel method of manufacturing gloves in which the necessity of the use of the kyle and the fourchette is eliminated.

It is the further object of my invention to provide a novel glove formed from strip material so assembled as to produce no objectionable seam.

10 It is the further object of my invention to provide a novel method of glove manufacture in which a single strip of glove material is folded over upon itself and suitably stitched to provide a finger and body portion for the glove.

15 It is the further object of my invention to provide a strip of fabric with a welt edge to form the glove of my invention.

It is the further object of my invention to provide a novel glove comprising strips of glove material laterally spaced in longitudinal alignment to provide an open-work glove.

20 It is the further object of my invention to provide a method of glove manufacture in which a continuous knitted strip of material is formed with alternate solid and strip sections and subsequently cut to be assembled in glove formation.

Figure 1 is a plan view of a strip of material having a welt edge which comprises the element of my glove.

25 Figure 2 shows a plan view of the novel glove of my invention manufactured from strips of material such as Figure 1.

30 Figure 3 is a cross-section showing a finger of the glove made from a one piece strip folded over at the top.

Figure 4 shows a modified form of finger formation of the glove. Two strips of material, one superimposed upon the other, are joined at the edges to finger form.

35 Figure 5 is a partial cross-section taken along the line 5-5 of Figure 2, in which the lateral joining of the strip is effected without a protruding seam.

Figure 6 is a modified form of strip assembly in which desirable decorative effects are obtained by spacing the strips and stitching with the decorative material.

40 Figure 7 shows the novel manner in which a single strip of material is used to form both index 45 finger and thumb.

Figure 8 shows a continuous length of knitted material in which the knitting is carried out so that strips are formed integrally with the solid portion of said continuous length of material. 50 This so formed continuous length of material is then cut as indicated so as to enable the glove to be formed therefrom.

Figure 9 is a plan view of a finger with the round tip formed by cutting the strip of material 55 that makes up the finger to the desired shape.

Figure 10 similarly is a plan view of a finger showing a square tip. This square tip is obtained by sewing together the straight strips of material without any cutting operation.

60 Figure 11 is a side elevation showing a cut section of Figure 8 after folding.

Referring now more specifically to the drawings, Figure 1 shows a strip of material which may be of any desired textile fabric such as silk, wool, 65 rayon or any material of this nature. It is also within the purview of my invention to use a strip of leather or skin material of any nature.

70 Around the edge of the strip of material 1 is a welt edge 2 which serves to prevent unravelling 75 of the strip and also has a useful function with

respect to the lateral edge to edge joining of a plurality of these strips into glove form. This welt edge 2 is of special utility when a textile strip is used.

Figure 2 is a plan view of an assembled glove 5 of my invention. Therein a strip 1 has been formed into finger form; folded over upon itself to form a finger and body of the glove as indicated. The folding over occurs at the finger tip 3. The sides of the overlapped strip 1 are then sewed 10 by securing stitching 4 to form an enclosure representing a finger and, in this case, the side of the glove. If desired the shape of the finger tip can be modified by regulating the distance of the stitching from the edge of the fabric at said 15 finger tip as shown at 5 whereby square or round tips, if desired, can be obtained. The strip thus formed into a finger and body portion of the glove is united to a similarly shaped finger and body portion by suitable stitching 6 along the body 20 of the glove. This stitching is carried up to the point 7 at which point the fingers begin.

Around the edge of the bottom of the body portion of the glove is a binding 8 which has utility in that it prevents any unravelling of the edge of the 25 glove, and further, may serve decorative purposes. Attention is directed to the fact that the thumb 9 and index finger 10 are formed from a single strip of material 11 by a method to be described more in detail hereinafter. It is further to be 30 noted that the various strips of material which go to form different fingers are preferably of various widths to obtain proper fitting effects.

In Figure 3 there is represented a cross-section 35 of a finger of the glove formed from a single strip of material 12 which has been overlapped at the end 13.

Figure 4 shows a modified form of a finger formation in which two strips 14 and 15 are superimposed and secured at the end by stitching 16. 40

Figure 5 shows a partial cross-section taken along the line 5-5 of Figure 2. Therein the strips 1 are secured by cross stitching 18 so that no protruding seam is formed. This is an important feature of my invention since it is very 45 desirable to eliminate any possibility of discomfort of a protruding seam within the glove.

Figure 6 shows two strips of material 19 and 20 spaced one from the other and secured by a stitching 21 in that manner. In this manner a 50 very attractive openwork glove can be obtained.

Figure 7 shows a cross-section of the thumb and index finger portion of my glove and indicates how a single strip of material 22 is used to form both index finger 23 and thumb 24.

55 In Figure 8 a continuous length of knitted fabric 25 is formed with separated strips 26 knitted integrally therewith. As shown, alternate sections of solid knitted portion and separated strip portions are formed in a continuous length. The continuous length is then severed, as along the line 27, forming sections which can be overlapped to form a glove. In the continuous length shown here sufficient strips and sufficiently wide body portions are knitted 65 so that a plurality of gloves can be made from each section. In this last method of manufacture, speed of operation and economy of manufacture are primary factors.

70 In Figure 9 is shown a round edge finger, 28 obtained by cutting the two superimposed strips to the desired shape 29 before stitching. Alternatively a strip could be folded over upon itself at the finger tip portion and then cut to this same shape. Further the stitching 30 could be 75

made in this desired line on the square ended fabric and the excess fabric cut away to form the round tip 29.

Figure 10 shows a square tip finger 31 formed by superimposing two strips of material and securing them together by stitching 32. This square tip can also be formed by the overlap arrangement explained hereinbefore.

In Figure 11 I have shown a cut section of Figure 8 properly folded over to form two gloves. The strips 26, upon folding, form fingers which are subsequently closed by stitching at the sides. The section is severed in the middle in the line 33 separating the two gloves. Each glove is subsequently stitched along this line. Slits 34 are appropriately placed and adapted to carry an inset thumb portion.

Alternatively the sections may be further cut midway between the strips, and the two cut sections superimposed, the fingers properly shaped and the stitching applied around the fingers and sides to form a glove.

I shall now describe a specific method of making the novel glove of my invention. Although any type of glove material may be used, in my process I shall speak specifically with reference to knitted textile fabric. On a knitting machine of the Rochel, flat or Jacquard type, I knit a long, narrow strip of the width on the order of $\frac{3}{4}$ of an inch. This width can be varied according to the width of the fingers of the glove it is desired to form therefrom. On the sides of this strip there are formed welt edges which serve to prevent unravelling and also provide a joining edge which makes it possible to form a seam between two such laterally disposed strips without an objectionable inward protrusion of the seam. Two such welt edge strips are then proportioned of the proper length, one superimposed upon the other as shown in Figure 2. A stitching is run around the finger portion and in the case of the little finger, the formation of which I shall first discuss, the stitching runs around the finger and down one side to form a little finger and the closed side portion of the glove. Two similar strips slightly longer than the strips used in the formation of the little finger, are then superimposed one upon the other and joined by stitching to form a finger and the body portion. The so joined strips are then attached as shown at 6 in Figure 2. This joining to the adjacent strip thus goes towards the forming of both the top and the palm of the glove as shown at I and I' in Figure 2. Similarly, other fingers can be formed.

The index finger and thumb may be formed from a single strip of the fabric as shown in Figure 7, by folding the strip in front to form the thumb and extending it to form a lapping upon itself to form the finger and body portion of the glove. The sides of the fingers are then stitched together to form a closure. A thumb may also be formed by simply folding over a single strip of the material and insetting it in an opening in the front of the body portion of the glove below the index finger.

I have spoken of a process involving two superimposed strips joined to form a section of my glove which joining is shown in Figure 4. It is to be understood that a single strip may be used instead of the two strips to form all of the fingers, the single strip being folded upon itself as shown in Figure 3, and secured at its edges as indicated hereinbefore.

When two square edge strips are united, a

square finger tip is formed. When a single strip is folded over upon itself a square finger tip is similarly formed. However, the shape of the finger tip may be varied by stitching inwardly of the edge of the material to form an arc over the finger tip thus producing a round finger tip. Alternatively, the end of the finger tip may be cut to the shape desired, such as a round edge and stitched in that form. Reviewing briefly what has been said above, the glove is formed from four longitudinally aligned and laterally joined strips of glove material as shown in Figure 2. These longitudinal sections of the glove can be formed either from two superimposed strips or from a single strip folded over upon itself. The sides of the fingers are formed by simply stitching together the strips at the edges as shown at 4. The body portion of the glove, constituting the top and the palm, is made by the lateral joining of the longitudinal sections as shown at 6.

This lateral joining of the longitudinally aligned strips is preferably effected by a cross stitching as shown at 18 in Figure 5. This cross stitching effects the joining of the laterally disposed strips without causing an inwardly protruding seam which would be a source of discomfort to the wearer. Any suitable stitch can be used to effect this purpose. If desired, a sufficient plurality of strips with welt edges may be integrally and continuously formed on the knitting machine so that the glove may be completed by simply cutting the fingers to shape as set forth hereinbefore.

Over this securing stitch an attractive, decorative stitch may be superimposed externally to emphasize the lines of the glove and add materially to its appearance.

The glove formed as indicated above, may have a wrist portion consisting of an independently knitted section or a simple binding may be effected on the bottom of the wrist for decorative purposes and to prevent any possible unravelling of the glove.

Although the glove has been formed from a plurality of strips whose width is equal to that of the fingers involved, it is also the object of my invention to make the single strip which has been formed to make a single finger from a plurality of strips laterally joined. Preferably, however, I use a single strip for a single finger. A glove formed according to the method indicated has excellent fitting qualities, especially when the width of the strips have been regulated according to the particular fingers involved. Thus, in the formation of the middle finger, a wider strip is used than in the formation of the little finger.

By the method I have set forth, I have eliminated a great number of steps hitherto regarded as necessary in glove manufacture and I have set forth a comparatively simple process for forming gloves of strips which can be inexpensively manufactured.

An alternative method of practicing my invention consists in knitting an endless length of fabric as shown in Figure 8 of the drawings, with alternate sections of solid and strip material. The solid portions go toward making up the body of the glove and the strip sections form the fingers. The continuous lengths formed, as indicated in Figure 8, are severed at the line 21. This severed portion is then folded over on itself, one solid portion forming the top of the glove and the other solid portion forming the palm of the glove. The strips form the fingers. A stitch-

ing is run down the sides of the strip portion therein and also at both edges of the strip.

In Figure 8 I have shown eight strips formed in the endless length of the material. This particular section is capable of making two gloves when properly folded. When this method of manufacture is used, a thumb portion is inset by the use of a single strip of material or by two, superimposed, properly secured strips of material. This last mentioned method provides an extremely simple and inexpensive method of glove manufacture. When the sections of Figure 8 are folded over upon themselves, they present an appearance similar to Figure 11. They can then be severed down the line 33 to form two gloves.

There are many modifications and combinations of methods of making gloves which suggest themselves from the steps set forth in my specification. I have set forth the combinations of different steps only by way of specific example. I intend to be limited by the appended claims only.

I claim:

1. The method of making a fabric glove which comprises knitting laterally joined selavage strips, separating the selavage strips between the selavage edges for a predetermined distance to provide finger portions, transversely cutting the strips to form a glove section, superimposing two such cut sections and securing the superimposed cut sections at the sides and around the edges of the finger portions.

2. A fabric glove comprising selavage fabric strips of substantially finger width laterally joined in the palm portion, said selavage fabric strips comprising the front and back of the fingers and being joined at the edges to form finger stalls.

3. The method of making a fabric glove which comprises knitting laterally joined selavage strips, knitting continuously with said laterally joined selavage strips separated selavage strips of a predetermined length to provide finger portions, transversely cutting the selavage strips to form a glove section, superimposing two such cut sec-

tions and securing the superimposed cut sections at the sides and around the edges of the finger portions.

4. The method of making a fabric glove which comprises knitting laterally joined selavage strips, separating the selavage strips between the selavage edges of adjacent strips for a distance sufficient to form finger portions of a length substantially twice that of the finger to be formed; transversely cutting the laterally joined selavage strips to form an integral glove section comprising laterally joined selavage strips at each end and separated selavage strips therebetween; folding the cut glove section upon itself at a point intermediate the separated selavage strips so that a face to face contact of the laterally joined selavage strips and the separated selavage strips is effected, and securing the folded over glove section at the edges to form the palm portion and finger stalls respectively of the glove.

5. In a method of manufacturing a fabric glove, the steps of forming the thumb and index finger of the glove by folding a finger width fabric strip upon itself to form a thumb portion; again folding the strip upon itself at a predetermined distance from the first fold to form an index finger portion, the line of both folds being perpendicular to the length of the strip; securing the folded strip at the side edges to form thumb and index finger stalls.

6. In a fabric glove, a thumb and index finger comprising a single finger width selavage fabric strip of substantially the same width throughout its length folded upon itself and secured along the side edges to form a thumb and index finger stalls.

7. A fabric glove comprising welt edge fabric strips of substantially finger width laterally joined in the palm portion by stitching within the welt edges so that no protruding seam is formed, said welt edge fabric strips comprising the front and back of the fingers and being joined at the edges to form finger stalls.

JOSEPH BLOOM.
